VALVE

Eddy K. Dayne, Glendora, and Wilbur G. Land, Anaheim, Calif., assignors to Bagdad Plastics Company, Phoenix, Ariz.

Filed Sept. 20, 1971, Ser. No. 182,307

Term of patent 14 years

Int. Cl. D23—01

U.S. Cl. D23—19

FIG. 1 is a side elevational view of a valve showing our new design;

FIG. 2 is an end elevational view thereof;

FIG. 3 is an elevational view taken from the side opposite that shown in FIG. 1;

FIG. 4 is an elevational view taken from the end opposite that shown in FIG. 2;

FIG. 5 is a top plan view thereof; and

FIG. 6 is a bottom plan view thereof.

We claim:

The ornamental design for a valve, as shown.
